(57) **CLAIM**

The ornamental design for a money box, as shown and described.

DESCRIPTION

FIG. 1 is a Front elevational view of a money box showing my new design;

FIG. 2 is a Rear elevational view thereof;

FIG. 3 is a Left side view thereof;

FIG. 4 is a Right side view thereof;

FIG. 5 is a Top plan view thereof;

FIG. 6 is a Bottom plan view thereof; and,

FIG. 7 is a Perspective view thereof.

The broken lines in the drawing depict portions of the money box that form no part of the claimed design.
